UNITED STATES PATENT OFFICE.

LOUIS EMILE DUBOIS, OF TORONTO, ONTARIO, CANADA.

LOOM.

SPECIFICATION forming part of Letters Patent No. 367,028, dated July 26, 1887.

Application filed January 14, 1887. Serial No. 224,340. (No model.)

To all whom it may concern:

Be it known that I, LOUIS EMILE DUBOIS, of the city of Toronto, in the county of York, in the Province of Ontario, Canada, manufacturer, have invented certain new and useful Improvements in Looms, of which the following is a specification.

The object of the invention is to provide a loom in which small feathers or small pieces of fur may be woven into a continuous web having a close but flexible back; and it consists in the peculiar combinations and the novel construction, arrangement, and adaptation of parts, all as more fully hereinafter described and claimed.

Figure 1 is a perspective rear view of my loom with a portion of its frame broken away, so as to exhibit more clearly my improvements. Fig. 2 is a sectional side elevation.

In the drawings like letters of reference indicate corresponding parts in each figure.

A is the main frame of the loom, substantially constructed and designed to support the working parts.

In my loom I employ three heald-frames, marked, respectively, B, C, and D, the main warp-threads *d* passing through the loops in the healds *a* and *b*, while the supplemental warp-threads *e* pass through the loops in the healds *c*. The warp-threads *d* are carried on

the roller E, which is supported in suitable bearings on the posts F, a pin, *f*, being inserted into one of the holes, *g*, made in the roller E for the purpose of preventing the said roller revolving when it is desired to hold the threads *d* taut. The threads *e* are carried on

the roller G, each separate thread being independently wound within a separate division formed on the said roller G, which roller is suitably journaled and held by friction suffi-

ciently to prevent it revolving except when drawn upon by the threads *e* as they require fresh length. This may be accomplished in various ways. In the drawings I have shown an eyebolt, *a'*, through the eye of which the

shaft of the roller G is passed. This bolt is passed through a standard, F, and is provided upon its threaded end with a thumb-nut, *b'*, by tightening which the shaft of said roller may be caused to bind against said standard, more or less, as may be desired.

The heald-frames B, C, and D are supported by chains or cords *H*, which pass over rollers

journaled in blocks I, which are supported, as indicated, from the frame A.

In order that the heald-frames may balance each other and also be capable of operating to accomplish the purpose of my invention, I connect the heald-frame B to the heald-frame D, and to balance the heald-frame C, I provide an open frame, J, which is connected, as shown, to the heald-frame C.

Four levers, K, L, M, and N, are connected, respectively, by the chains or cords O to the respective frames B, C, D, and J. These levers K, L, M, and N are pivoted on the frame A, and are connected by the chains or cords P to the levers Q, which are pivoted at right angles to the levers K, L, M, and N, either upon the floor or to the frame A. The free end of each of the levers Q is connected, re-

spectively, to the treadles R, S, T, and U, by pins in each lever Q fitting into slots made in its respective treadle. From this it will be seen that the treadle R is connected to the heald-frame B, and the treadle T to the heald-frame C, while the treadle S is connected to the heald-frame D and the treadle U to the open frame J.

Having now described the general construction of my loom, a few words will suffice to explain its operation.

Having set my loom to commence work, I place the small pieces of fur or small feathers upon the main warp-threads *d*, the supplemental warp-threads *e* being at this time supported above the said fur or feathers. I then operate the treadles R and T, so as to cause the threads carried by the heald *a* to lower past the supplemental threads *e*, which are carried by the heald *c*, which latter threads are simultaneously caused to rise by the action of the treadle T. The shuttle with the weft-thread is then thrown through the shed in the ordinary way, and as much ordinary weaving may then be done as thought desirable. When I wish the pieces of fur or small feathers to be woven very closely together, I use only one weft-thread before bringing the supplemental threads *e* again into action for the purpose of adding a fresh piece of fur or feathers, the number of weft-threads being increased if it is desired to make the fur light and open.

It will of course be understood that the lay *W* is operated as in ordinary hand-loom.

What I claim as my invention is—

1. The combination, with the block I and pulley carried thereby, of the heald-frames B D, cord or chain H, passed over said pulley and connected with said frames, the levers K M, cords O, connecting said levers and frames, the levers Q, treadles R S, and the cords P, connecting the levers K M and treadles, substantially as and for the purpose specified.
2. The combination, with the heald-frames B D, cords connecting said frames together, the heald-frame C and open frame J, cords connecting them together, as described, of the le-

vers K L M N, pivoted at one end, connections between said levers and frames, the levers Q and treadles R S T U, jointed together at their adjacent ends, and the cords or chains P, connecting each alternate lever Q with each alternate one of the said levers K L M N, substantially as described.

Toronto, December 31, 1886.

LOUIS EMILE DUBOIS.

In presence of—

CHARLES C. BALDWIN,
CHARLES H. RICHES.
